(57) **CLAIM**

We claim the ornamental design for the portfolio, as shown and described.

DESCRIPTION

FIG. 1 is a perspective view of the portfolio, particularly showing the inventive design thereof;

FIG. 2 is a front view thereof;

FIG. 3 is a rear view thereof;

FIG. 4 is a top view thereof;

FIG. 5 is a bottom view thereof;

FIG. 6 is a left side thereof;

FIG. 7 is a right side thereof; and,

FIG. 8 is an interior perspective view thereof.

The broken line showing in the above figures is for illustrative purposes only and forms no part of the claimed design.

1 Claim, 6 Drawing Sheets

FIG. 1

FIG. 2

FIG. 3

FIG. 4

FIG. 5

FIG. 6

FIG. 7

FIG. 8
